SURGICAL CLAMP

Michael James Moore, Box A-E,
San Luis Obispo, Calif. 93401

Filed Mar. 1, 1972, Ser. No. 231,086

Term of patent 14 years

Int. Cl. D24—02

U.S. Cl. D83—12 R

FIG. 1

FIG. 2

FIG. 3

FIG. 1 is a perspective view of a surgical clamp showing my new design;

FIG. 2 is a front elevational view thereof; and

FIG. 3 is a side elevational view thereof.

I claim:

The ornamental design for a surgical clamp, substantially as shown.
